UNITED STATES PATENT OFFICE.

BERNARD SCHECHTER, OF ST. LOUIS, MISSOURI, ASSIGNOR OF ONE-HALF TO GEORGE H. TONTRUP, OF ST. LOUIS, MISSOURI.

BRAKE-HANDLE.

1,267,280.

Specification of Letters Patent. Patented May 21, 1918.

Application filed October 26, 1917. Serial No. 198,598.

To all whom it may concern:

Be it known that I, BERNARD SCHECHTER, a citizen of the United States, residing at St. Louis, in the State of Missouri, have invented certain new and useful Improvements in Brake-Handles, of which the following is a specification.

This invention consists of improvements in brake handles of the drop type, which require less room for their operation, and in which the ratchet means is engaged only during the use or operation of the brake. The dropping of the handle causes disengagement of one ratchet from the part that operates the brake.

In the accompanying drawings forming part of this specification, in which like numbers of reference denote like parts wherever they occur,

20 Figure 1 is a sectional view showing the parts in operative position;

Fig. 2 is an end elevation showing the parts disengaged from operative position;

25 Fig. 3 is a sectional view on the line 3—3 in Fig. 1, looking in the direction of the arrows;

Fig. 4 is a section on the line 4—4 in Fig. 3, looking in the direction of the arrows;

30 Fig. 5 is a view on the line 5—5 in Fig. 2, looking in the direction of the arrows; and

Fig. 6 is a view on the line 6—6 in Fig. 2, looking in the direction of the arrows.

The brake handle 1 is pivoted on screws 2 which pass through the cam lugs 3 forming 35 part of the housing 4.

The brake staff 5 rises through the car floor (not shown in the drawings) being connected at its lower end with the brake rigging and at its upper part being received 40 in hollow ratchet bearing member or collar 6 and fastened therein and thereto by pins 7. This is more convenient than present practice, which is to weld together the staff and a stud depending from parts supporting 45 ratchet members.

At its top ratchet bearing member 6 terminates in enlarged portion 8, the upper edge of which is provided with ratchet teeth 9 adapted to grip and coöperate with ratchet teeth 10, both of which ratchets are inclosed 50 in collar 11 which is fastened by a pintle 12 having up-set ends 13 to collar 11 and to member 21.

The staff 5 passes pivotally through the

center of the hollow member bearing ratchet 55 9 and its continuation 21 passes through the hollow member 14 bearing the ratchet 10, screws 2 abutting the same after passing through the cams 3 and the wall of hollow member 14. The stop 15 engages on the outside of the wall of hollow member 14 when the brake handle is in the position shown in Fig. 1, that is, in operative position.

A pin 16 or other spring stop engages one end of spring 17 which at its other end abuts 65 against the shoulder 18 on the inside of hollow member 14 and when the handle is in the position shown in Fig. 1, the said spring 17 forces ratchet member 14 bearing the ratchet 10 into engagement with ratchet 9, 70 which ratchet 9 is in fixed relation to brake staff 5 by reason of the pins 12 and 13 and rotates therewith. When, therefore, handle 1 is in the position shown in Fig. 1, ratchets 10 and 9 are gripping each other and circumferential movement of handle 1 in the desired direction will cause ratchet 9 to turn brake staff 5 and to apply the brake. When this has been accomplished it is unnecessary 75 to return the handle 1 to its initial position 80 or to do anything with it except to allow it to drop by gravity, which results in cams 3 raising ratchet 10 out of engagement with ratchet 9 because handle 1 is pivoted by screws 2 to ratchet member 14. 85

The exterior of hollow member 14 is polygonal at 19 (preferably rectangular) in order to coöperate with the angular interior of the housing 4 at the point where the said housing comes in contact with the exterior 90 of the hollow member 14. By means of this polygonal engagement, when the handle 1 is moved circumferentially it causes the hollow member 14 to turn herewith and thus exercises considerable power thereon and on 95 ratchet 10 and thereby ratchet 9 and brake-staff 5 and in turn the brake rigging and brake.

The top edge of the collar 11 forms a bearing for the cam or cams 3. The housing 100 4, whether the handle 1 is in raised or lowered position, covers the spring 17 and top of the continuation 21 of brake staff 5 and thus forms a structure in which there is a saving of metal because of the cam or cam 105 members 3 serving the double function of collars and housing, while the ratchet inclosing collar 11 serves the double function

of acting as such inclosure or housing and also to afford a bearing for the cam or cams 3. Stop 20 limits the downward movement of handle 1.

5 While the spring 17 is convenient to keep the upper ratchet member spring pressed when not disengaged by the positive action accompanying the lowering of the handle 1, yet the said spring may be dispensed with 10 and the action of the parts being produced merely by the movement of the handle.

Having thus described this invention, I hereby reserve the benefit of all changes in form, arrangement, order, or use of parts, as 15 it is evident that many minor changes may be made therein without departing from the spirit of this invention, or the scope of the following claims.

I claim:

20 1. The combination of a hollow ratchet member, a brake staff fixed thereto, a second ratchet member mounted for detachable engagement with the first member, a brake staff extension passing through the second 25 ratchet member and fixedly related to the staff, said first ratchet member having a bearing part, a spring coiled about the protruding upper end of the extension for urging the second ratchet member into engagement with the first member, and a brake 30 handle pivoted to the second ratchet member for swinging in a vertical plane from its operative horizontal position to its inoperative vertical position alongside the brake 35 staff and having its pivoted end formed into a housing for inclosing the upper end of the staff extension and the coiled spring, the lower edge of the housing being formed into a cam for operating on the bearing part of 40 the first ratchet member to raise the second ratchet member from engagement with the latter when the handle is swung downwardly from its operative position to its inoperative position alongside the staff.

45 2. The combination with a pair of coöper-

ating ratchet members, one of which has a bearing part and the other formed with a polygonal part, means for urging the ratchet members into coöperating engagement with each other, and a brake handle having one 50 end formed into a housing inclosing the aforesaid means and pivoted to the second specified ratchet member, the interior of the housing substantially conforming to the polygonal part of said second ratchet member and pivoted for moving into and out of engagement therewith, the lower edge of the housing being of cam form for riding on the bearing part of the first ratchet member to disengage said ratchet members. 60

3. A brake handle comprising, in combination with a brake staff, a ratchet fixed thereto, a second ratchet mounted for movement into and out of engagement with the first ratchet, means resiliently urging the ratchets 65 into interlocking relation, said second ratchet having a stem part, and a brake handle lever having one end formed into a housing receiving the ratchet stem and pivoted thereto for swinging in a vertical plane 70 from a horizontal operative position downwardly into a vertical inoperative position alongside the brake staff, said housing having its wall underlying the lever body cut away to permit such downward swinging of 75 the lever, and the lower side edges of the housing being formed into cam portions extending upwardly at the opposite edges of said cut away part of the housing, the first ratchet having a part underlying and constituting a bearing surface for the cam portions whereby, when the lever is swung downwardly alongside the brake staff to inoperative position, said cam portions will operate upon the bearing surfaces to elevate 80 the second ratchet from engagement with the first ratchet. 85

In testimony whereof I hereunto affix my signature:

BERNARD SCHECHTER.
